UNITED STATES PATENT OFFICE.

PAUL KELECOM, OF LIEGE, BELGIUM, ASSIGNOR TO FABRIQUE NATIONALE D'ARMES DE GUERRE SOCIÉTÉ ANONYME, OF HERSTAL, BELGIUM.

DESIGN FOR A MOTOR-CYCLE FRAME.

No. 38,977.

Specification for Design.

Patented Dec. 31, 1907.

Application filed April 26, 1907. Serial No. 370,535. Term of patent 7 years.

To all whom it may concern:

Be it known that I, PAUL KELECOM, a subject of the King of Belgium, residing at 21 Place de Bronckhaert, Liege, in the Kingdom of Belgium, have invented a new, original, and ornamental Design for a Motor-Cycle Frame, of which the following is a specification.

My new design for a motor cycle frame is devised to provide a main frame in one piece, not broken by the introduction of the motor, and is distinguished by the feature that the upper tube, the intermediate tube, and the stirrup in one piece with the rear tube pass-

ing in the rear hub, are all three strictly horizontal and parallel.

The design is illustrated in the accompanying drawing, in which

Figure 1 represents a side elevation, and Fig. 2 a plan view.

What I claim is:

The ornamental design for a motor cycle frame, as shown.

PAUL KELECOM.
